UNITED STATES PATENT OFFICE.

CLAUD L. PATTERSON, OF GOODING, IDAHO.

DESIGN FOR AN ADVERTISING NOVELTY POST CARD.

Application filed October 7, 1922. Serial No. 3,898. Term of patent 14 years.

To all whom it may concern:

Be it known that I, CLAUD L. PATTERSON, a citizen of the United States, residing at Gooding, in the county of Gooding and State of Idaho, have invented a new, original, and ornamental Design for an Advertising Novelty Post Card, of which the following is a specification, reference being had therein to the accompanying drawing.

The drawing is a plan view of a post-card advertising novelty showing my new design.

What I claim is:

The ornamental design for an advertising novelty post card, as shown.

In testimony whereof I hereunto affix my signature.

CLAUD L. PATTERSON.
